ELBERT C. BOTTRELL, OF MILWAUKEE, WISCONSIN

FOLDING CRATE

Application filed April 30, 1930. Serial No. 448,584.

This invention relates to improvements in folding crates, particularly, although not solely, adapted for poultry and the like.

It is one of the objects of the present invention to provide a folding metal or wire crate which, when empty, may be collapsed into a flat, compact form for convenience in storage or transportation.

A further object of the invention is to provide a folding crate including a pan-like base or bottom member which will entirely contain therein in a compact manner, the side, top and end portions of the crate when the same is collapsed.

A further object of the invention is to provide a collapsible crate having folding side and end portions and means for locking said crate portions against undesired folding or collapsing when the crate is in its "set-up" condition.

A further object of the invention is to provide a folding crate which is of very simple construction, is strong and durable, is inexpensive to manufacture, and is well adapted for the purposes described.

With the above and other objects in view, the invention consists of the improved folding crate, and its parts and combinations as set forth in the claims, and all equivalents thereof.

In the accompanying drawing in which the same reference characters indicate the same parts in all of the views:

Fig. 1 is a longitudinal vertical sectional view of the improved folding crate in its "set-up" condition;

Fig. 2 is a cross-sectional view thereof taken on line 2—2 of Fig. 1;

Fig. 3 is a plan view of the crate in its folded or collapsed condition;

Fig. 4 is a cross-sectional view thereof taken on line 4—4 of Fig. 3;

Fig. 5 is an enlarged fragmentary sectional view of a crate end portion and the releasable means in latching position for holding the end in upright position; and

Fig. 6 is a similar view only showing the unlatched position of said means with a dotted line showing of the end as moved toward its flat, folded position.

Referring now more particularly to the drawing it will appear that the numeral 8 indicates a metallic, pan-like base member of rectangular form and having relatively low upstanding sides and ends 9 and 10 respectively.

Secured within said pan-like base member is a rectangular base frame 11 formed of a piece of wire of a suitable gauge. As portions of each side of the crate, a plurality of spaced-apart medially hinging or folding straps are employed, each strap comprising an upper or outer member 12 and a lower or inner member 13. The complementary members 12 and 13 of each pair are hinged together at their adjacent ends by pintles 14 extending through complementary rolled end portions 15. Each pair of strap members 12 and 13 are adapted to fold or hinge inwardly and to prevent outward breaking or folding when said strap members are in their vertical extended positions, the lower or inner end of each member 12 carries a slightly inwardly off-set tongue 16 adapted to engage the inner face of its complementary member 13 and thus prevent undesired outward folding.

The lower or inner end portions of the strap members 13 are bent about side portions of the base frame 11 so as to hinge or pivot thereon, while the upper or outer end portions of the strap members 12 are similarly bent about side portions of an outer rectangular frame 17 of a top member. In addition to said frame 17, the top member includes spaced apart transverse rods 18 and longitudinal rods 19. Each side of the crate is formed by the folding strap members 12 and 13 and by a pair of longitudinal rods 20 and 21 secured respectively to the strap members 12 and 13 and at right angles to the same.

Each end of the folding crate is formed of a frame including end rods 22 which are pivotally bent at their lower or inner end portions about an end portion of the base frame 11, and spaced apart transverse rods 23 secured at their end portions to the rods 22.

Adapted to cooperate with each end member to releasably hold the same in unfolded, vertical position, is a folding locking member extended between medial end portions of the

base frame 11 and the top frame 17. Said locking member comprises a lower strap member 24 bent about a portion of the base frame 11 so as to pivot thereon, and an upper strap member 25 bent about a portion of the top frame 17 so as to pivot thereon. Adjacent ends of the members 24 and 25 are hingedly joined, as at 26, and one of the members carries an inwardly off-set tongue 27 to prevent outwardly folding of said members, when extended, with respect to each other.

The upper portion of the strap member 25 is formed with a rectangular slot 28. There is slidably mounted on said strap member 25 a latch 29 having a T-shaped head 30 bent at right angles to the body portion of the latch member and extended through said slot 28 and movable therein. Secured to the upper or outer end portion of each end member of the crate is a plate 31 formed with a T-shaped opening or slot 32. The major portion of the slot 32 corresponds in size and is adapted to register with the slot 28 in the adjacent strap member 25, while the head of said slot 32 is of a sufficient size to receive therethrough the T-shaped head 30 of the latch 29.

In Figs. 1, 2, 5 and 6, the crate, and portions thereof are illustrated in open or "set-up" position. To attain this position, the top member is grasped and is pulled directly upwardly and this movement will cause all of the strap connections between the top member and the base frame to unfold, until all of the pairs of complementary strap members are extended vertically. Then, the end members are swung outwardly from folded flat positions adjacent the base member to vertical positions against their straps 24 and 25. In this position the top rods 23 of the end members will lodge immediately below the end portions of the top frame 17, securing said frame and top member in raised position.

The end members are releasably locked in their vertical positions by means of the latch means previously described. Initially, each latch 29 is adjusted so that it is in its uppermost position on its strap 25 and then its head 30 is passed through the head slot of the opening 32 in the adjacent plate 31. Then, by pulling the latch downwardly the head 30 will engage the plate 31 on opposite sides of the slot 32 whereby the end member is securely held to the unfolded strap 24-25. As the ends are held against folding in this manner, and as the ends support the top, when in vertical position, the crate can not collapse. To fold the crate it is merely necessary to raise the latches and disengage the same from the slotted plates 31 and then the ends are folded downwardly into the pan-like base. Next, all of the complementary strap members are caused to break inwardly and they fold upon themselves within the base member and the top is pushed thereonto. The folded position of the crate is shown in Figs. 3 and 4, and

the crate, when folded, is very compact, and the sides, ends and top thereof are all contained within the pan-like base member.

The improved folding crate is especially adapted for shipping poultry but it is, of course, susceptible of other uses. In its "set-up" condition it is very rigid and secure, while when folded, a number of said crates may be packed or stored in a minimum amount of space. Furthermore, the improved folding crate is both simple and novel, and is well adapted for the purposes set forth.

What I claim as my invention is:

1. A folding container, comprising a base member, a pair of side members foldable with respect to said base member and medially foldable upon themselves, a top carried only by said side members, another pair of rigid side members foldable only upon said base member, and latch means for releasably connecting said last-mentioned side members in unfolded position to said top to secure all of the parts in open, unfolded positions.

2. A folding container, comprising a base member, spaced-apart, medially folding straps hingedly connected at their inner ends to said base member, a flat top member, the outer ends of said straps being hingedly attached to side edge portions of the same, the strap members along a pair of opposed sides of the base and top members carrying side elements, rigid gate members for the other opposed pair of sides and hingedly connected to said base member, said gate members being bodily movable from folded positions against the base member to vertical positions between the base and top members, and means carried by adjacent straps for releasably engaging said gate members in their vertical positions.

3. A folding container, comprising a rectangular, pan-like base, a rectangular top, a pair of opposed, medially foldable sides hingedly connected to opposed sides of the top and base, and another pair of rigid sides hingedly connected only to the other opposed sides of the base, all of the sides being foldable entirely into the confines of said base against the bottom thereof and the top being moved by the medially foldable sides in parallelism with said base and into the confines of the base.

4. A folding metal crate, comprising a rectangular, pan-like base, a rectangular base frame mounted therewithin, a rectangular top, medially folding straps hingedly secured at their opposite ends to said base frame and to said top, longitudinal side elements carried by the straps on the two sides of the crate, a pair of rigid end gates hingedly connected to opposite end portions of the base frame, and latch members carried by the straps on the ends of the crate and releasably engageable with said end gates when the

same are unfolded with respect to the base frame, all of the parts when in folded positions being confined within said base.

5. A folding container, comprising a rectangular, pan-like base, a rectangular base frame mounted therewithin, a rectangular top, medially foldable sides hingedly connected to opposite sides of the base frame and top, medially folding straps hingedly secured at their opposite ends to end portions of the base frame and top, a pair of rigid end gates hingedly connected to opposite end portions of the base frame, and latch members carried by said straps and releasably engageable with said end gates when the same are unfolded with respect to the base frame, all of the parts when in folded positions being confined within said base.

In testimony whereof I affix my signature.
